Application November 9, 1939, Serial No. 303,640
In Great Britain November 21, 1938

4 Claims. (Cl. 209—437)

This invention relates to reciprocating sluice boxes.

The chief object of the present invention is to provide a completely automatic reciprocating sluice box for the continuous concentration of minerals which, when once set for operation with a given mineral, does not require any attention, nor does it require any additional wash water or back pumping.

Another object of the invention is to provide a simple, compact and highly efficient machine of high capacity which is capable of automatically and continuously classifying and concentrating minerals irrespective of their different specific weights and varying individual volumes.

Still another object of the invention is to eliminate the necessity of classifying material to a definite mesh by separate classifying machines before passing the same to the concentrating machines.

A particular object of the invention is to provide a sluice box which is more efficient in use and more economical in operation than previously proposed sluice boxes.

A further object of the invention is to provide novel means for removing the mineral concentrates, which means does not depend on gravity alone for its proper operation and which may be adjusted to meet requirements such as varying particle sizes and specific weights.

The sluice box according to the present invention comprises an inclined table divided into sections comprising a plain portion of constant width constituting a settling plane, and a portion having a part of increasing depth and preferably diminishing width, constituting a concentrating plane, mineral removing means, preferably adjustable and preferably, also, rotatable, being situated at the portion of greatest depth, and means for reciprocating the table.

Means are conveniently provided for altering the inclination of the table.

It is preferred that the means for removing mineral concentrates be such that no appreciable quantity of water is taken from the table. In the preferred form of the invention the concentrates removal means comprises a rotating brush rotating in a direction opposite to that of the flow of the wash water and so mounted that the periphery thereof may extend above the surface of the table to a variable extent. This brush is conveniently intermittently rotated, as by a ratchet and pawl mechanism, but it may be continuously rotated.

Below the surface of the table in the neigh-

bourhood of the concentrates removing means is provided a concentrate container in which the rotary brush is mounted, the container being provided with a sloping bottom and means for discharging the concentrates therefrom. The discharging means preferably comprise a screw conveyor arranged automatically to discharge the concentrates without appreciable loss of wash water. In an alternative arrangement there is provided a container having a sloping bottom terminating in a pair of outlet ports provided with shut-off means such that when one port is shut the other is open. The outlet ports are individually connected by lengths of flexible hose or the like to collecting tanks. The container hoses and collecting tanks are all filled with water to avoid drawing from the wash water. Concentrates collected by the brush are carried down into the container where they are washed off by the disturbance of the water in the container and, then, fall down and pass out through one of the ports and so into one of the tanks. When that tank is full the closure means are reversed whereupon the filled tank may be removed for emptying or replacement by an empty tank which is filled with water before being connected to the hose leading to the container.

In order that the invention may be clearly understood and readily carried into effect, constructional embodiments of the invention are hereinafter more fully described by way of example with reference to the accompanying drawings which are given for the purpose of illustration but not limitation. In these drawings—

Figure 1 is a plan of a portion of the machine having the table partly broken away to expose the driving mechanism.

Figure 2 is a side elevation of Figure 1.

Figure 3 is a plan of another portion of the machine having the table partly broken away to expose the re-coil springs.

Figure 4 is a side elevation of Figure 3.

Figure 5 is a section on line 5—5 of Figure 3.

Figure 6 is a transverse section, partly in elevation, of means different from those shown in Figures 1 to 5, for dealing with the concentrates.

Fig. 7 is a vertical longitudinal middle section through a device, as shown in Fig. 6, and

Fig. 8 is a side elevation of an adjustable support.

In practice, it is convenient to triplicate the set of apparatus comprising the settling and concentrating planes, together with the means for collecting and removing the concentrates and the attendant mechanism, to form a single machine,

and as the sets of apparatus are substantially similar the following description is substantially confined to a single set of apparatus.

Referring to the drawings, a is the settling plane, and a^1 is the concentrating plane of the table. The settling plane is of constant width and inclined in the direction of the length of the table, whilst the concentrating plane is of gradually reducing width and of increasing depth. The surface on either side of the concentrating plane is flat and in the same plane as the settling plane. The boundary walls of the concentrating plane are vertical and have affixed along their length, a strip of metal a^2 which overhangs the concentrating plane. At the lower end of the concentrating plane is provided an aperture a^3 through which protrudes a portion of the periphery of a rotary collecting brush (hereinafter referred to). Deflector plates a^4 are fixed to the table surface and an adjustable plate a^5 (at the tailing edge of the brush) is mounted so that it can slide upon and be locked to them. The deflector plates and the sliding plate prevent the entry of gangue down the sides of and behind the brush.

The table is mounted on channel side members b supported on wheels b^1 which in turn are supported on rails c . The whole machine is given an even to and fro motion by means of a connecting rod d connected at one end to a rod b^2 supported in a bracket b^3 fixed to the side-members b and at the other end to an adjustable out-of-centre position of male and female grooved-faced crank-webs d^1 on a shaft d^2 driven from any suitable source by a belt d^3 . The crank-webs permit of adjustment of the stroke of the connecting rod. Re-coil springs e (see Figures 3, 4, and 5) are mounted under compression against stationary brackets e^1 on either side of the front axle b^4 of the machine, and when they are equally adjusted they tend to throw the machine backward and forward uniformly, thus relieving the table surface of shock, preventing undue disturbance of the layer of concentrates and taking up any backlash that may develop in the drive.

The collecting brush shown at f , is mounted on a shaft f^1 running through arcuate slots formed in the side walls of the container g which latter is secured in a water-tight manner to the underside of the sluice-box. The arcuate slots are made water-tight by means of rubber and steel washers tightened by screw-glands as shown at g^1 (Figure 5). The shaft f^1 is hung on radius arms h whose upper pivotal points are in alignment with the contact line of the brush with the tailing edge of the concentrating plane a^1 . The lower ends of the arms h are connected to rods h^1 which in turn are connected to a shaft h^2 mounted in bearings h^3 . A handle h^4 enables the shaft h^2 to be moved angularly for the purpose of raising and lowering the brush in the aperture a^3 with the periphery of the brush always in contact with the tailing edge of the concentrating plane. The brush having been adjusted in position it is prevented from moving accidentally by means of a spring-loaded locking pin h^5 engaging in one of a series of holes in a fixed plate h^6 . The upper pivotal points of arms h are mounted on plates h^7 (Fig. 8) which are in turn mounted on the channel side members b and are adjustable in a vertical direction by means of set screw h^8 and slots h^9 . The adjustable plate a^5 is moved nearer to or further from the said tailing edge so that it will terminate at or close to the periphery of the brush each time that the position of the latter has been adjusted. The

brush is given an intermittent rotary motion against the flow of water down the table by means of a double-acting pawl j pivoted on an arm j^1 and acting on a ratchet wheel j^2 fixed on the shaft f^1 carrying the brush. The ratchet wheel is driven by the link j^3 connected to the bar j^4 mounted in guides b^5 . The bar j^4 is reciprocated by means of a rotary crank j^5 fixed to one or other of the shafts j^6 of reduction gears (not shown) enclosed in a casing j^7 and geared to the shaft d^2 the crank being connected to the bar j^4 through link j^8 , arms j^9 and j^{10} , link j^{11} , bell-crank j^{12} and link j^{13} . Adjustment of the number of ratchet-wheel teeth taken per stroke is achieved by varying the position of the link j^{11} along the arm j^{10} . Different speeds of rotation of the crank j^5 are obtained by fixing it to the appropriate shaft j^6 . The to and fro motion of the machine causes the link j^{11} to pivot about its point of connection to the arm j^{10} but owing to the length of the link j^{11} the motion at its point of connection to the bell-crank j^{12} is almost a straight line, thereby not affecting the ratchet wheel movement. When adjusting the inclination of the machine, the lock-nut j^{14} connecting the link j^{11} to the bell-crank j^{12} is slackened to allow the corresponding end of the bell-crank to take up a new position along the slot in the link j^{11} .

30 The concentrates are automatically removed from the container g by means of a conveyor screw k rotating in a casing k^1 and whose outlet k^2 is arranged above the table so that no appreciable quantity of water is lost. The conveyor is driven by a shaft k^3 (Figure 5) and gearing k^4 and k^5 , the shaft k^3 being common to the driving gear of the conveyors of all the containers and being driven by any suitable means such as an electric motor (not shown) mounted on channel member b at one end thereof.

In an alternative construction (see Figure 6) for the removal of the concentrates, the container l is provided with a pair of outlets l^1 controlled by valves l^2 and connected by flexible hoses l^3 to stationary collecting tanks l^4 which are initially full of water to prevent drawing off any of the wash water from the table. When one of the tanks l^4 is full the corresponding valve is closed, the end of the corresponding hose is disconnected from the tank and the tank is removed and replaced by another tank filled with water.

The inclination of the machine is adjusted by a simple left and right hand threaded screw m and scissor legs m^1 (see Figures 1 and 2) the screw being rotatable in nuts m^2 by means of a ratchet actuated by a handle m^3 . The scissor legs are pivoted at their inner ends to the nuts, at their lower ends to the axle b^6 of the wheels b^1 and at their upper ends to a rod b^7 fixed to the bracket b^3 . The axle b^6 is connected to the bracket b^3 by radius arms of which one is shown at m^4 . The inclination having been adjusted the whole is locked in position by any suitable means, e. g., slotted arms standing up from the axle b^6 and lock nuts on the rod b^7 to lock the slotted ends of the arms to the rod b^7 .

Modifications within the scope of this invention are: a collecting brush extending across the full width of a flat sloping surface; continuously instead of intermittently rotating collecting brushes; the use of corduroy, felt or other suitable material wrapped around a cylinder instead of brush bristles; a belt or similar contrivance with a rough surface passing over a roller or the like.

75 In operation, the container (with the collecting

tanks below it when such tanks are used) is first filled by the flow of water through the brush. The normal gravitational flow of the ore and water fed in at the higher end of the machine, is converted into a reciprocating motion by the continuous to and fro motion of the sluice-box, which motion causes the minerals, owing to their greater specific weight, gradually to settle to the bottom of the mixture whilst the latter is flowing over the settling plane. The minerals, upon reaching the concentrating plane, and having previously settled to the bottom, are now gradually pressed together from the sides owing to the gradual slope and decreasing width of the concentrating plane, being assisted by the flow of water and the to and fro motion of the sluice-box, whilst the gangue spilled over the boundary walls of the concentrating plane is carried away rapidly by the flowing water over the higher flat surface and away from the collecting brush, whereupon the process is repeated, commencing at the succeeding settling plane. Meanwhile the minerals continue their downward path towards the brush, continually pushing gangue away to the sides owing to the diminishing width and increasing depth of their volume, and thus arrive finally at the brush as concentrates.

The brush, being adjustable, is adjusted for the particular ore to be treated such that the height of the brush above the surface of the sluice-box is approximately equal to the depth or thickness of the mineral-concentration, thus allowing any overlying gangue to be washed over the brush and away to the next settling plane by the flow of the water. The minerals, on the other hand, cling to the rough surface of the brush which projects above the surface of the concentrating plane and has a width and depth substantially equal to those of the concentrated layer of minerals. Owing to its intermittent rotary motion, the brush allows settlement of the minerals including all the fines on said surface and thence carries the minerals below the surface of the sluice-box to deposit them into the container.

The to and fro motion of the container together with the rotating motion of the brush create a continual disturbance of the water in the container, which motion clears the concentrates from off the brush allowing them to be shaken finally down into the container or tanks as the case may be, whence they are removed as already explained.

The distance between the brushes and the edges of the concentrating planes being adjustable by the vertical adjustment of the supporting plates of the brush locating radius arms, the brush at the end of the first concentrating plane can be so adjusted as to allow only concentrates say of minus 60 mesh to be carried down to the receiving tanks. All concentrates of plus 60 mesh would pass over the brush and be collected at the end of the second concentrating plane, the brush of which would be adjusted to remove only say minus 40 mesh the remainder passing over to be collected by the third brush which would be adjusted approximately equal to the largest mesh size of the valuable mineral content in the feed ore. Thus separate groups of concentrates of different mesh grading can be obtained on this one machine.

The necessity for previous classification of the feed after milling and before passing to the concentrating sluice-box is eliminated as any large size particles of gangue which should happen to pass on to the surface of the table cannot jam in

nor choke the apertures due to the rotation of the brushes, and will consequently roll over the brushes and be washed away over the end of the table. Variations in the mesh of the valuable mineral content of the ore, however, are dealt with in the manner explained above.

We claim:

1. In a sluice box for concentrating minerals, the combination with a concentrating table having a slightly inclined bottom terminating at a horizontal discharge edge, of a cylindrical rotary brush having upstanding bristles, said brush being mounted adjacent said discharge edge with its axis extending parallel to said discharge edge 15 below the horizontal plane of the latter, means supporting said rotary brush for adjustment to several positions in which its peripheral surface projects to a greater or lesser extent above said plane, said supporting means including lever arms 20 fulcrumed on an axis extending parallel to and adjacent said discharge edge, a plate extending over the rear portion of said rotary brush and being adjustable to various positions, whereby, for each adjusted position of said brush, the front 25 edge of said plate may be positioned in contact with the peripheral surface of said brush approximately at the highest point thereof, and means for unidirectionally rotating said brush to cause movement of its peripheral surface adjacent said 30 discharge edge in a direction substantially opposite to that of the flow of water coming from said concentrating table.
2. In a sluice box for concentrating minerals, the combination with a concentrating table having a slightly inclined bottom terminating at a horizontal discharge edge, of a substantially cylindrical rotary mineral collecting element, said element being mounted adjacent said discharge edge with its axis extending parallel to said discharge edge 35 below the horizontal plane of the latter and its peripheral surface projecting above said plane and forming a gap with said discharge edge and means including lever arms fulcrumed on an axis extending parallel to and adjacent said 40 discharge edge for adjustably supporting said rotary element, so that it may be selectively adjusted to several positions in which its peripheral surface projects to a greater or lesser extent above the horizontal plane of said discharge edge without changing the width of the gap between said 45 peripheral surface, and said discharge edge.
3. In a sluice box for concentrating minerals, the combination with a concentrating table having a slightly inclined bottom terminating at a horizontal discharge edge, of a cylindrical rotary brush having upstanding bristles, said brush being mounted adjacent said discharge edge with its axis extending parallel to said discharge edge 55 below the horizontal plane of the latter, and its peripheral surface forming a gap with said discharge edge, the solid core of said brush being disposed entirely below the horizontal plane of said discharge edge and some of its bristles projecting upwardly beyond said plane.
4. A sluice box, as claimed in claim 2, including a plate extending over the rear portion of said rotary elements and being adjustable to various positions, whereby, for each adjusted position of said rotary elements, the front edge of said 60 plate may be positioned in contact with the peripheral surface of said rotary elements approximately at the highest point thereof.
